SEWING MACHINE

Thomas E. Monroe, New York, N. Y., assignor of one-half to William R. Donaldson, Northport, N. Y., and one-fourth to William R. Donaldson, as trustee; William R. Donaldson administrator of said Thomas E. Monroe, deceased

Continuation of application Serial No. 373,976, January 10, 1941. This application October 20, 1944, Serial No. 559,579

15 Claims. (CL. 112—98)

1

This invention relates to improvements in sewing machines.

It is an object of the invention to provide a portable sewing machine of an improved type and in this aspect the invention constitutes an improvement upon the disclosures of my Patent No. 2,152,203, issued March 28, 1939, and upon my Patent No. 2,206,484, issued July 2, 1940. The present application is a continuation of my earlier filed co-pending application for United States Letters Patent, Serial No. 373,976, filed January 10, 1941. The method of stitching disclosed herein is the subject of my co-pending application for United States Letters Patent, Serial No. 559,580, filed October 20, 1944.

A further object of the invention is to provide, in a portable sewing machine, means for forming a stitch having locking characteristics more closely approximating those of full size conventional machines, while avoiding the complex mechanism common to such machines.

A further object of the invention is to provide mechanism adapted to the production of a double loop stitch, or stitch in which the loops are taken alternately from two threads, with a single needle.

A further object of the invention is to provide improved means for making such a double loop stitch with alternate loops of different lengths, producing an improved locking action.

With these and other objects which will appear in the following description in mind, the invention consists in the combinations and arrangements of parts and details of construction which will now be described in connection with the accompanying drawing and then pointed out more particularly in the appended claims.

In the drawing:

Fig. 1 is a side elevation of a portable sewing machine embodying the invention in a preferred form and with the upper portion broken away to show the drive mechanism in central vertical section;

Fig. 2 is a section taken on the line 2—2 of Fig. 1 and further showing the drive mechanism;

Fig. 3 is a vertical section taken on the line 3—3 of Fig. 1 and showing the operating parts on an enlarged scale;

Fig. 4 is a horizontal section taken on the line 4—4 of Fig. 3;

2

Fig. 5 is a horizontal section taken on the line 5—5 of Fig. 3 and showing particularly the lower part of the machine, comprising the thread holding and loop forming mechanism;

5 Figs. 6 and 7 are fragmentary views similar to Fig. 5 and showing the parts in different positions assumed in operation of the device;

Fig. 8 is a vertical cross section taken on the line 8—8 of Fig. 3;

10 Fig. 9 is a horizontal section taken on the line 9—9 of Fig. 8 and showing the construction of the shuttle;

Figs. 10 to 14 inclusive are views of part of the thread handling mechanism shown in Figs. 5 to 15, 7 on an enlarged scale and showing the parts in the positions assumed at different stages of the operation;

15 Fig. 15 is a schematic showing of the stitch formed by the machine as seen from the top or obverse side of the fabric;

Fig. 16 is a side view of the stitch of Fig. 15, the layers of fabric being indicated by dot and dash-lines;

20 Fig. 17 is a view similar to Fig. 16 but showing a modified form of stitch; and

Fig. 18 is a plan view of a portion of the fabric table, showing particularly the apertures for accommodating the needle and feeding foot;

25 Referring particularly to Figs. 1 and 3, the machine of this invention comprises a U-frame A, to one arm of which is attached a needle operating head B; a thread-handling head C being similarly attached to the other arm. The fabric 30 being placed upon the table D forming the top of the thread-handling head C is held thereon by presser foot E and advanced along the table D by a feeding foot F, cooperating with an inclined extension G of the table D. Needle mechanism 35 similar to that of my above-mentioned copending application is employed and comprises generally a hooked or barbed needle H, attached to a plunger I, and a pin J reciprocable within the needle and serving together with the barbed end to form an eye in the tip of the needle. Thread from spools K and L is supplied to the needle by means of a shuttle M having a cam surface N, and a shoe O supported by a spring P and adapted

40 to be operated by feeding foot F.

45 50

Method of stitching

The method of stitch formation will be best understood from Figs. 10 to 16 inclusive and involves the production of alternate and interlocked loops from the respective threads *k* and *l* taken from spools *K* and *L*, in the following manner: The machine being threaded and the threads passed through the small holes *o*, *o*, or thread guides in shoe *O* as shown in Fig. 10, the descending feeding foot *F* in advancing the fabric pushes the shoe *O* against cam *N* into the position of Fig. 11 so that the descending needle *H* enters the shoe to the right of thread *k* as shown in Fig. 11, the motion of the pin *J* being retarded so that the eye in the needle *H* is open. At this stage, the pressure of the feeding foot *F* against the shoe is relaxed so that the shoe returns to the position of Fig. 10 as shown in Fig. 12, forming a loop in thread *k* within the eye of the needle. The needle upon being drawn upwards through the fabric carries the loop with it. On the next downstroke of the needle it passes through the previously formed loop and the sequence of events is repeated. The tension in thread *k* produced by the needle pulling on the loop, however, moves shuttle *M* across so that the shoe *O*, on being moved toward the shuttle by the feeding foot *F*, now encounters the opposite side of the cam *N*, pushing the shoe into the position of Fig. 13 so that the needle enters the same to the left of thread *l*, as shown in that figure. Upon relaxing of the pressure of the feeding foot *F* against the shoe, the shoe returns to the position of Fig. 14 with a loop from thread *l* caught by the needle. The upstroke of the needle thus draws a loop from thread *l* (instead of thread *k*) upward through the fabric and through the loop previously formed from thread *k*. Repetition of this operation results in the formation of the stitch shown schematically in Figs. 15 and 16 in which each thread, *k* or *l*, passes through the fabric at alternate stitches, so that the loops on the top or obverse side of the fabric, as shown in Fig. 15, present the appearance of a simple chain stitch but with the loops of the chain coming alternately from the two spools. On the reverse side the stitch presents the appearance, as shown in Fig. 16, of parallel straight courses of thread, two stitches in length and staggered as shown. By using threads *k* and *l* of different colors, as indicated in Fig. 15, a stitch of decorative character is readily produced.

As will be seen, the stitch of the invention possesses locking characteristics not to be found in ordinary chain stitches. In an ordinary open chain stitch, it is often possible for the loops to disengage successively when tension along the line of the stitch is applied to the fabric. This tendency, particularly when a stitch of proper length relative to the fabric thickness is employed, is largely obviated in the stitch of the invention, in which the loops come alternately from different threads so that tension on one thread results rather in catching and firmly holding the other, than in assisting it to unravel.

In certain cases and particularly where very heavy fabrics are being sewed, it is desirable to increase the locking effect of the stitch by varying the tension on the spools. As shown in Figure 17, the application of greater tension to thread *l* than to thread *k* results in the formation of shorter loops in the former, producing a reverse bend in the loops of the latter, as shown. As shown to the right of Fig. 17, when the thread starts to unravel the long loop from the thread *k*

falls back and catches the short loop of thread *l*, thus stopping the unraveling.

Drive mechanism

The machine for producing the stitch as described is operated entirely by the up and down motion of a needle plunger body *I* which reciprocates through apertures *2* and *3* in a frame *4* fastened within the outer casing *5* of the needle operating head *B*. This reciprocating motion is produced through a pitman *6* attached to the upper end of plunger *I* by a pin *7* and driven through wrist pin *8* by crank *9* mounted on a shaft *10*, journaled in a bushing or bearing *11* at the upper end of the head *B*. Shaft *10* is preferably driven by an electric motor (not shown) through a flexible shaft *12* in a casing *13* as shown, it being understood that these terminate in an electric motor which may be plugged in at any convenient outlet. Shaft *10* carries on wheel *15* an annular gear wheel *16* driven by the shaft *12* through a pinion *17*. To permit hand operation of the machine when desired, the wheel *15* is formed with a rim *18* and carries the annular gear wheel *16* loosely within a recess formed in the wheel *15* and between the wheel and a face plate *19* affixed thereto. As best shown in Fig. 2, a gear wheel *16* is formed with apertures having radial faces *20* and cam faces *21* and receiving balls or discs *22*, this arrangement constituting a unidirectional clutch. As will be understood, counterclockwise rotation of wheel *15* by hand unclutches the gear wheel *16* by carrying the balls or discs *22* against the radial faces *20*, thus permitting hand operation. On the other hand, counterclockwise rotation of the gear wheel *16* forms a driving connection between gear wheel *16* and the shaft *10* through the cam faces *21* and discs *22*.

Variation in the stitch produced is provided for by mounting the crank *9* upon a shaft *23* affixed thereto and passing eccentrically through shaft *10*. Affixed to the other end of the shaft *23* is an arm *24* having a boss *25* adapted to enter any of a number of indentations *26* in face plate *19* and to remain therein by reason of the spring of arm *24*. By means of this arrangement, seating of the arm *24* in any of the various angular positions provided for varies the effective length of crank *9* and thus varies the length of the stitch produced.

Needle operating and fabric feeding mechanism

The needle plunger *I* bears the needle *H* fastened to it by means of block *27* and screw *28*, and has, by reason of the crank arrangement just described, a simple reciprocatory movement. This plunger also serves, through mechanism about to be described, to impart the required movements to the feeding foot *F* and the needle pin *J*. Needle pin *J* terminates at its upper end in a T-head *29* within a cutout *30* in the plunger *I* and feeding foot *F* is carried by a body portion *31* formed with an angle *32* adapted for engagement by the lower end of plunger *I* and with a crosswise abutment *33* adapted to seat under an abutment *34* formed on the plunger *I* as shown in Fig. 3. The body portion *31* includes also a projection *35* adapted to limit its stroke and wings *36* passing around plunger *I* and formed with cam rises *37* adapted to engage the T-head *29*. The body portion *31* of feeding foot *F* is pressed against the plunger *I* by means of a spring *38* fastened to the latter by screws *39*.

At the commencement of the downstroke of plunger I, the feeding foot F, through angle 32 and abutment 33, is positively carried along with it and the needle pin J, through T-head 29 and rise 31, is also carried with the plunger. By reason of the incline of table G, the feeding foot is urged to the left during this downward movement, so that the angle 32 disengages from the lower end of the plunger I. At this time or shortly thereafter, T-head 29 encounters a rise 40 formed in the casing 5, disengaging abutments 33 and 34 by pressing the feeding foot body 31 back against spring 38. Continuing motion of the plunger I brings the upper end of cutout 30 against T-head 29, carrying the same over the rise 40 into a recess 41 where it stops. At this point the lower end of the pin J will be slightly below the level of the fabric. Meanwhile the plunger I, continuing to move, will have carried the lower end 42 of spring 38, which is slanted as shown, over the corresponding slant of the body 31 of feeding foot F just above the angle 32, and the lower end of the plunger engaging the curve of feeding foot F below the angle 32 will have wedged the feeding foot to the left out of pressing contact with the fabric.

As the upstroke of the needle commences the barb 44 of needle H engages the lower end of pin J closing the eye of the needle with a loop of thread therein and thereafter returns the needle pin J to the position of Fig. 3. The feeding foot rises directly upward with the plunger I, being held against the same by the lower end 42 of spring 38 (at this time below the angle 32), until projection 35 engages an adjustable stop 45 on the wall of casing 5, which engagement stops the movement of the feeding foot. The plunger I, however, continues to move upward until it reaches the position of Fig. 3, at which point the abutment 34 slips back under abutment 33 and the angle 32 slips back under the lower end of the plunger I under the influence of spring 38, thus returning the parts to starting position for the next stitch.

To coordinate the stroke of the feeding foot F with the stroke of the plunger I for various lengths of stitches, the stop 45 is carried on a pin 46 within a vertical slot 47 in the casing 5 and is positionable by means of a thumb nut 48 at various heights thereon to correspond with the various strokes of the plunger I produced by setting of the arm 24 as described above.

The fabric is conveniently held on the table D by the presser foot E urged downward by a weight 49 and slidably mounted on a track 50 attached to the head B by means of clips 51 and guide pins 52, the presser foot being formed with an opening 53 to permit passage therethrough of the needle and feeding foot as described.

Thread handling mechanism

The fabric supporting tables D and G, previously referred to, are formed with openings 54 and 55, respectively, under the needle and under the feeding foot (Fig. 18), the former opening serving to permit passage of the needle and the latter to permit the feeding foot F to press against the shoe O within the head C through the fabric.

As best shown in Figs. 3 and 5 to 8, the shoe O is carried on a spring P fastened by means of screw 56 to a frame member 57 imbedded in the casing body 58 of the head C and is formed with a grooved upper surface 59 extending downwardly at an incline somewhat less than that of the table G so that the fabric moving down the same under

the feeding foot F urges the shoe O inwardly (to the right in Fig. 3), the rounded end or nose of shoe O accordingly engaging the cam N so that the shoe is wedged to one side into the position of Fig. 6 or 7, depending upon the position of the cam N. Cam N is controlled, through the shuttle M upon which it is carried, by the tension of the threads k and l passing through openings 59 and 60 at the ends of shuttle M. The shuttle M slides back and forth on a frame 61 formed on or attached to the frame member 57 and having a cut-out 62 limiting the movement of shuttle M by means of a pin 63 upon the latter. To lower friction, a wheel 64 may be mounted upon the pin 63 to furnish a riding surface for the nose of the shoe O after it has been pushed to one side or the other by the point of cam N.

With this arrangement, it will be understood that, starting in the position of Fig. 5, for example, the shoe will engage the left side of cam N (looking toward the cam) so that the shoe will be deflected sidewise into the position of Fig. 6, the needle picking up a loop from the thread k. When the shoe returns to the position of Fig. 5, and the needle rises and draws the loop with it, the tension created upon thread k moves the shuttle M over to the left (looking toward the shuttle) so that the cam N is positioned on the opposite side of the shoe O in preparation for the next operation. On the next downstroke of the feeding foot, the shoe O accordingly engages the opposite side of the cam N and is deflected into the position of Fig. 7 so that the needle now picks up a loop from the thread l. By this means the stitch described above, and having loops formed alternately from two threads, is produced.

Thread tensioning arrangement

The invention contemplates a very simple, but nevertheless effective method of thread tensioning. As best shown in Figs. 3 and 5 to 8, the spools K and L are carried in generally cylindrical recesses formed in the body 58 of the head C and the threads k and l passing upwardly over guide surfaces 65 are given the required slight tension by reason of their wrap around the guide surfaces and the consequent friction produced. The spools are held within the recesses by means of a cover plate 66 attached to the body 58 by hinges 67 and having formed with it an upper portion 68 constituting part of the table D and depending portions 69 constituting the upper side walls of the thread housing. No spindles for the spools are required, these being held in approximately the proper longitudinal position by means of bosses 70 and 71 on the body 58 and cover 66 respectively.

As it may be desired under certain conditions to produce a single chain stitch, I have provided means for immobilizing shuttle M when desired, these taking the form of slides 72 carried by means of pins 73 and slots 74 on the depending portions 69 of the cover 66. Either of these slides, by means of a button 75 attached to the pin 73, may be set in the position of Fig. 5 so as not to interfere with the motion of the shuttle M or may be slid over so as to hold the shuttle in either of its extreme positions. As will be apparent, when the shuttle is so held the shoe O will always engage the same side of cam N and accordingly a stitch will be formed from a single one of the threads k and l.

This action of the slides 72, controlled by button 75, would obviously permit of the producing of a number of stitches from one of the spools of

thread which may be of one color, then the stitches may be shifted by this mechanism to the thread from the other spool, which may be of another color; in this manner the slide mechanism 72 permits of decorative sewing in any manner desired, using any number of stitches of one color as against any number of stitches of the other color. This produces the possibility of distinctive decorative combinations in the sewing.

Operation

In preparing to operate the machine, the frame A, provided with a felt or rubber surfaced base 16 for that purpose, is clamped to a chair arm or table edge or other convenient location and the motor (not shown) is plugged in. Spools K and L are placed in the thread holder and the respective threads are brought through the notches 59 and 60 and passed through the holes in the nose of the shoe O. Wheel 15 is now turned by hand to pick up both threads and the loops above the table are pulled out with a needle or other instrument so as to bring the loose thread ends above the fabric table D, G. The fabric is now inserted under presser foot E and feeding foot F and the machine is in condition for operation.

The length of stitch is selected by setting arm 24 to a desired position and stop 45 by means of thumb nut 48 is set to adjust the feeding foot motion correspondingly by means of suitable indicia (not shown) on the outside of the casing. Stop 45 may also be set with relation to the plunger I by trial, when the latter is at the upper end of its stroke. In operation the needle plunger moves downwardly to a point where the needle is about to enter the fabric, at which time the needle pin J, being held back by rise 40 as described, opens the eye of the needle H (this releasing any loop of thread about the needle). Shortly thereafter the feeding foot, which has been moving downwardly and to the left and thus advancing the material under the needle, is freed from its engagement with the lower end of the plunger I and the abutment 34 so that the fabric is stationary at the time the needle point enters it. The needle, continuing to move, enters the fabric and passes through it and through the aperture 54 into the shoe O which by this time, through the action of the feeding foot F and the cam N, has been positioned to one side as shown in Fig. 11. Continued motion downward of the needle plunger I results in the feeding foot F being shoved aside, permitting the shoe O to return to the position of Fig. 12 and results further in the needle pin J, through its head 29 and the upper edge of the cut-outs 30, following the needle through the fabric to a point just above shoe O. Upon the return stroke, the hook of the needle picks up the loop of thread and the barb 44 of the needle encounters the lower end of the needle pin J thus closing the eye of the needle about the thread. Further motion lifts the needle pin J along with the needle so that T-head 29 passes out of depression 41 over the rise 40 and returns to the position of Fig. 3. The feeding foot F, in the manner described above, follows the needle plunger I vertically upward to the point where projection 35 engages stop 45 and then stops, coming back to engagement with the plunger I under the bottom of the plunger and abutment 34 upon the plunger completing its upward stroke.

If it is desired to make the stitch of Fig. 17 for increasing the locking effect, either spool (L, as shown in Fig. 8) may be reversed end for end

so that it unwinds in the same direction as the other spool (counterclockwise in Fig. 8) the path of travel in this event being shown in broken lines at 1'. The resulting sharper bend around the guide 65 increases the tension on spool L as compared with spool K. In consequence, the loop formed from spool L having first had the succeeding loop from spool K formed through it is then drawn back by the tension on the thread as the cloth is advanced and by the tension produced in forming the second succeeding loop resulting in the stitch as shown in Fig. 17.

The above described mechanism, as will be seen, is capable of forming stitch patterns which are variable depending not only on the physical characteristics of the threads employed but on the selective operation or control of the thread carrier or shoe O by means of the members 75. Thus a line or a portion of a line of stitches may be formed of a single thread from one of the spools K or L depending on which of the members 75 is in position for controlling the selective actuation of the thread carrier, or a second line of stitches or a second portion of a given line may be formed from thread from the other spool by the reverse operation of the members 75, all as described above. Also when desired, the stitches of one type or character of thread may be formed alternately with stitches of a different thread, the latter stitch pattern resulting from the operation of the machine with both members 75 in the positions shown in Figure 5. Such variations of the stitch pattern may be effected without rethreading the machine to effect a change from one pattern or order of stitches to another, since the thread carrier O retains the ends of the threads in position for selective engagement by the needle mechanism in regularly recurring order or in a different selected order, as mentioned, depending on the position of the cam N which can be controlled operatively by means of the members 75. The improved machine thus enables an operator, when desirable, conveniently to vary selectively in a desired order the physical characteristics of the stitches whether those characteristics relate to color of thread, length of stitches, or form thereof, and while mechanism illustrative of the invention has been shown and described it will be apparent that variations of such mechanism may be utilized within the spirit, and embodying the principles, of the present improvements.

What is claimed is:

1. In a sewing machine, a fabric supporting table, means for advancing a fabric intermittently along said table, a reciprocable hooked needle, means for reciprocating said needle through the fabric to a point below said table during each dwell in the said intermittent movement, means for holding two sources of thread supply below said table, and means for positioning thread for engagement by said needle alternately from the said sources of supply, comprising a thread carrier positionable to place a thread from either of said sources of supply at the said point, and actuating means for the said thread carrier comprising a member adapted to be yieldably pressed against the lower side of the fabric in the path of movement of the said fabric advancing means.
2. In a sewing machine, a fabric supporting table, means for advancing a fabric intermittently along said table, a reciprocable hooked needle, means for reciprocating said needle through said fabric to a point below said table during each dwell in the said intermittent movement, means

for holding two sources of thread supply below said table, and means for positioning thread for engagement by said needle alternately from the said sources of supply, comprising a thread carrier and actuating means for the said thread carrier including a member adapted to be yieldably pressed against the lower side of the fabric in the path of movement of the said fabric advancing means and means for lifting the said fabric advancing means out of pressure engagement with the fabric after the said needle has descended into position for engagement with a thread.

3. A sewing machine according to claim 2, in which the said means for positioning thread include a cam positionable to either side of the said member, and thread guiding means at each side of the said cam whereby tension on a thread from either source of thread supply when engaged by said needle is adapted to move the said cam to deflect the thread carrier into position for engaging thread from the other source of thread supply with the said needle.

4. In a sewing machine, a fabric supporting table, means for advancing a fabric intermittently along said table, a reciprocable hooked needle, means for reciprocating said needle through said fabric to a point below said table during each dwell in the said intermittent movement, means for holding two sources of thread supply below said table and means for positioning thread for engagement by said needle alternately from the said sources of supply, the last said means comprising a member having a needle engaging surface and a thread guide on each side thereof, means for moving said member to bring threads carried by both said guides to either side of said needle, and means for pressing said member toward said needle to bring said surface in contact with said needle and engage the nearer thread therein.

5. A sewing machine comprising a reciprocable needle operating member, a fabric support beneath said member, a needle having a thread engageable portion operable by said member to and from a thread engaging position beneath said support, a thread retaining and releasing member reciprocable with respect to the needle during portions of the reciprocating movements of the latter, a movable thread-carrier beneath said support and having a thread-end receiving portion arranged to receive the thread engaging portion of the needle on each downward stroke thereof, means cooperating with said carrier for causing the latter to move relative to said needle in a direction to effect engagement of the end portion of the thread in the carrier by said thread engaging portion of the needle while the latter is within said carrier, and means for effecting operation of said thread retaining and releasing member for retaining the engaged portion of the thread in the thread engaging portion of the needle during the upward stroke of the latter and for releasing said thread above the fabric during the initial portion of the subsequent downward stroke of the needle.

6. A sewing machine adapted to form successive inter-engaging loop stitches on the obverse side of a fabric comprising a support for the fabric, a reciprocable needle carrier above the support, a needle carried thereby provided with means for engaging thread beneath the support and drawing successive thread loops upwardly through the fabric and through the respective previously formed loops and releasing each loop about the needle, a plurality of sources

of thread of different physical characteristics, a movable thread-carrier beneath said support adapted to receive and retain end portions of thread of said sources and located in a position for receiving the thread engaging portion of the needle on each downward stroke thereof, means for actuating said thread carrier in timed relation with respect to the movements of said thread engaging portion of the needle for effecting engagement of one of said thread portions with said needle portion whereby upon each upward stroke of the needle a loop of said engaged thread is drawn upwardly through the fabric and through the previously formed loop and is released about said needle on the succeeding downward stroke thereof, and means for effecting the selective actuation of said thread carrier relative to the thread engaging portion of the needle for causing engagement of said threads by said thread engaging portion of the needle in a selected order to provide a stitch pattern determined by said order of selection.

7. A sewing machine adapted to form successive interengaging loop stitches on the obverse side of a fabric comprising a support for the fabric, a reciprocable needle carrier above the support, a needle carried thereby provided with means for engaging thread beneath the support and drawing successive thread loops upwardly through the fabric and through the respective previously formed loops and releasing each loop about the needle, a plurality of sources of thread of different physical characteristics, a movable thread-carrier beneath said support adapted to receive and retain end portions of thread of said sources and located in a position for receiving the thread engaging portion of the needle on each downward stroke thereof, means for actuating said thread-carrier to different positions in regularly recurring order and in timed relation with respect to the downward strokes of the needle for effecting engagement by the needle of said thread portions within said carrier in a given order to form a stitch pattern corresponding to the order of engagement of the threads by said needle portion, and means for controlling the operation of said thread-carrier actuating means for varying the order of thread engagement by said thread engaging portion of the needle for correspondingly varying said stitch pattern.

8. A sewing machine adapted to form successive interengaging loop stitches on the obverse side of a fabric comprising a support for the fabric, a reciprocable needle-carrier above the support, a needle carried thereby provided with means for engaging thread beneath the support and drawing successive thread loops upwardly through the fabric and through the respective previously formed loops and releasing each loop about the needle, a plurality of sources of thread of different physical characteristics, a movable thread-carrier beneath said support adapted to receive and retain end portions of thread of said sources and located in a position for receiving the thread engaging portion of the needle on each downward stroke thereof, means for actuating said thread-carrier into said positions in a given sequence for effecting engagement by said thread engaging portion of the needle of said thread portions in a given order to provide a stitch pattern determined by said order of engagement, and a plurality of selectively operable members each movable to an

operative position for varying characteristically the order of movement of said thread-carrier to thread engaging positions for correspondingly modifying the stitch pattern.

9. In a sewing machine, a fabric supporting table, means for advancing a fabric intermittently along said table, a reciprocable hook needle, mean for reciprocating said needle through said fabric to a point below said table during each dwell in the said intermittent movement, means for holding a source of thread supply, a shiftable hollow thread carrier having an open upper end and an internal needle engaging surface and a thread guide offset laterally from said surface, means biasing said carrier to a position wherein said surface is in axial alignment with said needle, releasable means operable against the action of said biasing means during each down stroke of the needle in shifting the carrier laterally to a position wherein the needle enters the carrier on the side of the thread guide remote from said surface, and means for effecting the release of said shifting means while said needle is in said last mentioned position whereby said biasing means moves said carrier laterally to effect engagement of the thread in said guide by said hook and effects contact of the needle with said surface prior to the succeeding upward stroke of the needle.

10. In a sewing machine, a fabric support, a reciprocable hooked needle above the support, means for reciprocating the needle to cause the hook thereof to pass through the support to a position beneath the same, a source of thread supply, a shiftable hollow thread carrier beneath the support provided with a needle engaging surface and a laterally off-set thread guide for directing thread from said source of supply into said carrier, means for shifting said carrier laterally from a normal position during each down stroke of the needle for causing the latter to enter the carrier at the side of the thread therein remote from said surface, and means for restoring said carrier to normal position to move the thread in the carrier into engagement by the needle and to move said surface into contact with said needle prior to the succeeding upward stroke of the needle.

11. In a sewing machine, a fabric support, a reciprocable hooked needle above the support, means for reciprocating the needle to cause the hook thereof to pass through the support to a position beneath the same, means for holding two sources of thread supply, a shiftable hollow thread carrier beneath said support provided with an internal needle engaging surface normally aligned with said needle when the carrier is in an intermediate position, said carrier having a pair of thread guides each positioned at one side of said surface for directing thread into said carrier from one of said sources, mechanism for effecting the shifting of said carrier laterally during each down stroke of the needle to a position wherein the needle hook enters the carrier on the side of one of said threads remote from said surface, means for restoring said carrier prior to the succeeding upward stroke of the needle to move the adjacent thread into engagement by said needle hook and to move said surface into contact with the needle, and means for controlling the shifting of said carrier in one lateral direction or the other for effecting the engagement by the needle selectively with one of said threads or the other.

12. In a sewing machine, a fabric supporting table, means for advancing a fabric intermit-

tently along said table, a reciprocable needle having a hook in one side thereof, means for reciprocating said needle through said fabric to a position below said table during each dwell in said intermittent advancement, means for holding two sources of thread supply below said table, and selectively operable means for causing said hook to engage thread from either of said sources, the last said means comprising a looping member provided with a guide for each of said threads located normally on the side of the needle axis opposite the hook side thereof, means for moving said looping member relative to the needle axis to a position wherein the guide of the selected thread directs a portion of said thread transversely of the hook side of the needle, and means for moving said looping member to normal position while the needle is in lowered position and thereby moving said portion of the thread against the needle for engagement by the hook thereof for forming a series of stitches in a pattern determined by the operation of said selectively operable means.

13. In a sewing machine, a fabric supporting table, means for advancing a fabric intermittently along said table, a reciprocable needle having a hook in one side thereof, means for reciprocating said needle through said fabric to a position below said table during each dwell in said intermittent advancement, means for holding two sources of thread supply below said table, and selectively operable means for causing said hook to engage thread from either of said sources, the last said means comprising a looping member provided with a guide for each of said threads located normally on the side of the needle axis opposite the hook side thereof, means for moving said looping member relative to the needle axis alternately to positions wherein the guides of said threads direct portions of the respective threads transversely of the needle side of the hook, and means for moving said looping member to normal position while the needle is in lowered position and thereby moving the respective portions of the thread against the needle for engagement by the hook thereof for forming alternate loop stitches of the respective threads.

14. In a sewing machine, a fabric supporting table, means for advancing a fabric intermittently along said table, a reciprocable needle having a hook in one side thereof, means for reciprocating said needle through said fabric to a position below said table during each dwell in said intermittent advancement, means for holding two sources of thread supply below said table, means comprising a looping member providing a guide for each of said threads located normally on the side of the needle opposite the hook side thereof, means for moving the looping member relative to the needle axis to positions wherein one of said guides or the other directs a portion of the respective threads transversely of the hook side of the needle, means for moving the looping member to normal position while the needle is in lowered position during each reciprocation of the needle and thereby moving the said respective thread portion against the needle for engagement by the hook thereof, and manually operable selector means for controlling said movements of the looping member for forming successive stitch loops of one of said threads.

15. In combination, in a chain stitch sewing machine comprising a fabric feeding means, a pair of thread sources, a reciprocable needle provided with a hook for engaging the thread from

13

either of said sources to form interengaged stitched loops, thread guide means for thread from said sources operable to two positions in each of which a section of thread from one of said sources is positioned for engagement by the needle hook, means for controlling the operation of the thread guide means for effecting movement thereof to said positions alternately whereby the needle forms alternate stitch loops of thread from said sources, and means for producing a tension differential on said threads from said sources for shortening the stitch loops formed of one of said threads and elongating the stitch loops formed of the other thread independently of said fabric feeding means.

THOMAS E. MONROE.
